T. BELL

VULCANIZER

Filed May 13, 1927

Fig. 3.

R. A. Thomas

WITNESS:

Thomas Bell

INVENTOR

BY *Victor J. Evans*

ATTORNEY

UNITED STATES PATENT OFFICE.

THOMAS BELL, OF RICHMOND, VIRGINIA.

VULCANIZER.

Application filed May 13, 1927. Serial No. 191,187.

My present invention has reference to a vulcanizer, and has for one of its objects the provision of a vulcanizer that dispenses with the employment of air bags and by whose use a plurality of tires, tubes or the like may be simultaneously cured and repaired.

A further object is the provision of a vulcanizer that includes a metal trough-like body that also serves as a container for water or like fluid which is heated by electricity, the said body, at the sides thereof, having curved projections which are concaved, a mold being arranged centrally and longitudinally in the top of the body, together with means, in the nature of presser plates, that are movable by screws into the mold and into the concaved sides of the body, whereby a tire of the ordinary construction may be treated in the mold, while the concaved sides take care of tires, either of the ordinary or balloon type, whose side walls are to be cured.

A still further object is the provision of a vulcanizer that includes a trough-like body having a mold in the top thereof and having concaved side projections whose inner walls are concaved, the body being inclosed in a casing that has openings in the sides thereof for the projecting sides of the body, said casing being filled with asbestos or other non-heat conducting material but carrying removable heater coils arranged below the bottom of the body so the water in the body will be heated, the said body having its sides provided with upwardly extending downwardly arched arms from each of which is hung a rod or bar carrying a presser plate, the said plates being disposed opposite the concaved sides of the body and being influenced by screws toward such sides, the arms supporting therebetween a support for another screw that operates an expandible presser of particular and novel construction which is arranged in the mold, and whereby tires can be treated in the mold or in the concaved sides of the body.

For a more definite comprehension of the invention reference is to be had to the following specification and the drawings which accompany and form part of this application, with the understanding that the draw-

ings illustrate one satisfactory embodiment of the invention, from which such changes may be made as fairly fall within the scope of what is claimed.

55

In the drawings:

Figure 1 is a sectional view of the improvement approximately on the line 1—1 of Figure 2.

Figure 2 is a side elevation of the improvement with parts broken away and parts in section.

Figure 3 is a perspective of one of the hanger rods.

Figure 4 is a fragmentary elevation looking toward the inner side of one of the up-standing arms.

Figure 5 is an elevation of the inner presser member, with parts in section.

As disclosed by the drawings, my improved vulcanizer contemplates the employment of a metal block 1. The block is of trough-like formation and is designed to have received in the bottom thereof a quantity of water, indicated by the numeral 2. The top of the block provides a mold 3. The mold has its bottom round in cross section and its sides straight and spaced from the straight sides of the block proper. The mold 3 is concaved or rounded longitudinally.

75

Preferably, the lower corners of the block are rounded inwardly and the ends thereof are inclined from the said rounded corners inwardly to the top of the block. The sides of the block are integrally formed with outwardly projecting portions 4 which are segmental in form and which are concaved longitudinally as at 5.

80

The projections 4 pass through complementary shaped openings 6 in the sides of a casing 7. The projections thus hold the casing on the block. The casing has its ends inclined outwardly to its bottom and the base or bottom of the casing, indicated by the numeral 8, is removable. The casing, for the major portion thereof, is filled with a heat retaining packing 9, but there are arranged in the bottom of the casing removable heater coils 10. The coils are attached to a suitable source of electricity which heats the water 2 of the hollow trough-like block

90

95

100

1 and which likewise heats the block itself. Arising centrally from the top of the block, at the sides thereof, there are outwardly arched arms 11. These arms are 5 preferably removably secured to the block by means 12. The arms are comparatively narrow, and the upper ends thereof have pins 13 passing transversely therethrough. The pins 13 also pass through elongated 10 openings 14 in hanger rods 15. The rods 15 are provided with other openings 16 disposed right-angularly with respect to the openings 14, and through the openings 16 the ends of the arms 11 pass. Each hanger 15 rod has a thickened portion through which there is a central elongated slot or opening 17, and the lower end of each hanger rod 15 has fixed thereon a laterally extending presser plate 18. The presser plates are 20 disposed opposite the center of the concaved thickened or enlarged sides 4 of the body 1. Passing through the openings 17 there are screw members 19. These screws are also guided through openings in the arms 11 and 25 engage with nuts 20 that are let in pockets 21 in the said arms. The screws have upper hand wheels 22 provided with hubs 23 disposed opposite and engageable with the hanger arms.

30 As far as the description has progressed it will be seen that tires to be treated may be received at either or both of the concavities 5 of what I have termed the side extensions 4. In reality these extensions are in the nature of lugs. The hanger rods 15 are freely hung from the arms 11 and are susceptible to vertical movement thereon. Thus, when the screws are operated to influence the arms toward the tire to be treated, the presser 40 plates 18 on the said arms may be properly adjusted with respect to the part of a tire with which they are to engage.

Seated in depressions 24 in the inner and widened lower ends of the arms 11, above 45 the pockets 21, there is a bridge plate 25. Threaded centrally through the plate 25 there is a screw 26 that has an upper hand wheel 27. The lower end of the screw has a ball rod which is swiveled in a block 28 that is 50 centrally secured on the inner face of a concaved plate 29. The screw 26 is also threaded through an expander plate 30 and this plate 30 is in contact with segmental plates 31 whose lower and thickened ends rest in the 55 sides of a concaved plate 29. The plates 29 and 31 provide the presser elements which engage with a tire to be treated in the mold 3.

By the employment of my improvement it will be seen that at least three tires can be 60 treated simultaneously. It will also be noted that I have entirely dispensed with the employment of air bags and from experience I have found that the screws which actuate the presser plates render the device easily operated and with the employment of only a

small amount of physical exertion can accomplish their purpose in a successful and more expeditious manner than by the employment of air bags. While I have described the part 3 as the inner mold of the device and 70 have shown the same integrally formed with the block 1, the same may be separately constructed from said block, so that interchangeable molds may be employed. When, however, the mold is integrally formed with the 75 block, fillers may be arranged therein to compensate for tires of different sizes. The operation of the screw 26 for the inner expander not only presses the plate 29 against the tire in the mold 3, but imparts a longitudinal movement to the plate 30, and the ends of this plate contacting with the segmental plates 31 of the expander spread the same outwardly to force the side walls of a tire against the mold. Of course, the device 80 is provided with a suitable normally closed opening whereby water may be fed into the trough-like hollow block or body.

Having described the invention, I claim:—

1. A vulcanizer comprising a hollow metal 90 block having arcuate projections on the sides thereof which are concaved longitudinally to provide side molds and having an inwardly extending mold in the top thereof, presser plates movable into the central inwardly extending and the concaved side molds, and means for heating the block.

2. A vulcanizer comprising a hollow metal body designed for the reception of water in the bottom thereof, said body having its sides integrally formed with arcuate projections which are concaved longitudinally, its top extending inwardly from its sides and from thence downwardly merging into a round bottom disposed above the bottom of the 105 block, the said concaved sides and central portions of the block providing molds, hanger rods loosely suspended from the sides of the block, presser plates thereon, revoluble means engageable with the rods for exerting a pressure thereagainst for forcing the presser plates into the side molds, an expansible presser plate for the central mold, revoluble means for expanding the presser plate in said mold, and means for heating the body.

3. A vulcanizing machine including a hollow metal block designed for the reception of water therein and having arcuate projections on the sides thereof which are concaved longitudinally and which provide molds, an arcuate mold in the top of the block, a casing having openings in the sides thereof to receive the side molds of the block therethrough, said casing adapted for the reception of a heat retaining packing and for removable heating elements, curved arms arising centrally from the sides of the block, vertically movable hanger rods pivotally supported from said arms, a presser plate on each rod, screw members movable through the 120

arms and through the hanger rods and having head portions engaging with the latter for influencing the presser plates into the side molds, a presser plate for the central mold comprising an arcuate member, said metal plates contacting with the inner sides of said member, an expander plate between the said

metal plates, and a screw swiveled to the arcuate plate, threaded through the expander plate and guided between the arms, for the purpose set forth.

In testimony whereof I affix my signature.

THOMAS BELL.
